(57) **CLAIM**

The ornamental design for a drive unit portion of a motor grader, as shown and described.

DESCRIPTION

FIG. 1 is a top left rear perspective view of a drive unit portion of a motor grader showing our new design;

FIG. 2 is a right side view thereof;

FIG. 3 is a left side view thereof;

FIG. 4 is a rear view thereof;

FIG. 5 is a front view thereof; and,

FIG. 6 is a top view thereof.

The broken line showing of the interior detail of the wheels is included for the purpose of illustrating environmental structure and forms no part of the claimed invention.
